W. DE PAUK

PRINTING FRAME

Filed July 9, 1925

Inventor
William De Pouk.
by: Hazard and Miller
Atty.

UNITED STATES PATENT OFFICE.

WILLIAM DE PAUK, OF LOS ANGELES, CALIFORNIA.

PRINTING FRAME.

Application filed July 9, 1925. Serial No. 42,477.

My invention is a printing frame and method of printing photographs; and comprises a frame for a tissue paper dodging operation to print through a negative and the dodging paper.

My printing frame is constructed of two main frame members with a smoothing frame pivoted between the frames cooperating with a bead on one frame and a groove in the other so that the dodging tissue paper may be stretched tight in order to perform the dodging operation thereon. The frame has a recess for the plate or for a frame in which the plate may be secured and the dodging marks with a soft pencil to darken, doping the tissue to lighten and cutting out parts of the tissue may be readily done by looking through the negative towards a source of light.

My invention as to the structure of the frame and the method of operation would be more readily understood from the following description and drawings in which;

Figure 1 is a perspective view of my frame in its closed position illustrating a dodging tissue prepared for printing with a plate positioned thereon.

Fig. 2 is a cross section of Fig. 1 on the line 2—2 illustrating the cooperating main frames, clamping frame and co-acting bead and groove to draw the dodging tissue paper tight.

Fig. 3 is a plan view of the frame wide open showing the clamping frame in sections.

Fig. 4 is a cross section on the line 4—4 of Fig. 3 in the direction of the arrows, showing the three element hinge.

The printing frame comprises a lower open frame 1, an upper open frame 2 and a clamping frame 3 between. These frames are all secured together by a single hinge 4 which are shown with straps 5 through which wood screws 6 engage into the wooden frame members 1 and 2 and with a bead 7 bent around the hinge pin 8 and holding the clamping frame 3 in position. An upper and a lower hinge is shown, but as many as will be required to give accurate alignment will be used.

Beads 9 are shown as formed of a bent strip of metal with flanges 10 and web 11 bent reversely at the web, and are secured to the top and bottom 12 and 13 and to the left and right sides 14 and 15 of the top frame 2. These beads need not meet exact-

ly at the corners and are preferably chamfered or bevelled to a sufficient extent to form an opening level with the bottom of the clamping frame. It is preferable to have the flanges of the bead of the same thickness of metal as the clamping frame 3. A series of grooves 16 are formed in the bottom frame 1, forming slots of the same shape as the beads 9 and forming a fairly tight fit therewith.

The upper frame 2 is provided with a recess 17 in which a plate may be accurately positioned or a printing frame may be inserted. In Fig. 2 a plate 18 and a printing paper 19 are indicated positioned in the recess 17 and a printing frame 20 is indicated by the dotted lines, held in place by any suitable fastener as the thumb screw 21. The means for holding the negative and printing paper in position may be of any suitable character or may be a separate frame entirely so that I do not wish to be limited to any particular details.

The manner of inserting the tissue paper in the frame is as follows:

The frame would be open in the position shown in Fig. 3 and a sheet of tissue paper of a suitable size will be inserted over the bottom frame 1 after the clamping frame 3 has been tilted fully upward. The tissue paper is designated by the numeral 22 and will pass over the surface of the metal tensioning frame 3 which is a rectangular metal frame with substantially the same size opening as the main frame and secured to the bottom frame by screws 24. The clamping frame will then be lowered over the paper so that it will occupy the position 22' underneath the clamping frame and the position 22'' above the tensioning frame. If the paper is cut slightly larger than the frame this allows it to be slightly stretched by hand, otherwise it may be smoothed and the weight of the clamping frame will hold it firmly in position.

The top frame 2 is then hinged to bear downwards on the lower frame so that the beads 9 press the paper into the grooves 16 into the position shown by 22''. This action stretches the paper forming a smooth drum like surface in the opening of the frame. The frame is then clamped in this position by locking bar 25, which is formed with a series of slots 26 engaging headed pins 27 secured to the bottom frame and having bayonet slots 28 with open ends 29 engaging

headed pins 30 on the edge of the upper frame. A ring or the like 31 is secured to one end of the locking bar to manipulate it.

The method of printing photographs by utilizing dodging tissue paper clamped in my frame is substantially as follows:

As above described, Fig. 1 shows the dodging tissue paper tightly clamped and drawn tight in the frame with a plate 18 held in the recess 17. As is well known, the objects of dodging prior to printing photographs, is to tone down high lights or to lessen the density of shadows so that the details will be brought out more clearly in the print. These details may be sufficiently distinct in the negative but will not show as accurately in the print. I may however, increase the brilliancy of the high lights and also the density of the shadows if desired.

I support the frame in any suitable manner so that the light shines through the paper and through the plate. Places where it is desired that less light pass through than the plate would transmit are darkened with pencil marks using a soft pencil as indicated by the numeral 32. Places to transmit still less light may have a heavier dodging mark or cross mark as indicated at 33. If more light is required than the tissue paper would transmit it may be doped with material such as used for retouching negatives to give a greater translucency as indicated by the numeral 34, the ordinary dope as sold by dealers in photograph supplies for retouching negatives is satisfactory or an oil or shellac may be utilized to give increased transparency to the tissue paper. In portions of a picture which should have a still brighter light part of the paper may be cut away with a sharp instrument as indicated at 35.

It is apparent that these relative densities of the dodging tissue paper may thus be utilized in printing to transmit more or less light in accordance with the wishes of the operator and his skill in determining the correct amount of shading or increasing the transparency of the tissue paper. After the paper is properly prepared the photograph may be printed by placing a suitable printing paper over the plate clamping it in position and printing in the usual manner; or else a printing frame with a plate and printing paper secured therein may be held in the recesses 17 of the upper frame.

It is obvious that my frame may be utilized for printing from negatives which may readily be attached to glass by adhesive tape or held stretched across the recesses 17 with thumb tacks or the like. With the use of my frame and tissue paper the corners of the paper may be marked and after printing folded and filed away with the negative so that reprints may be obtained giving substantially a duplicate effect of the first

prints, as one may indicate on the edge of the tissue paper the kind of paper used in printing, the light utilized, the intensity of the light and the time of exposure.

My invention may be considerably modified both in structural details and in method of operation, without departing from the spirit thereof.

Having described my invention, what I claim is:

1. A printing frame comprising in combination a tensioning frame having a peripheral surface over which tissue paper may be drawn, a clamping frame positioned to fit on the outside of the tensioning frame and adapted to grip the outer edge of the tissue paper, and means to hold a negative in proper position from the sheet of tissue paper smoothed by tensioning and clamping frames, whereby light may be transmitted through the paper and negative.

2. A printing frame as claimed in claim 1, having in addition a cooperating bead and a groove adjacent the said peripheral surface, adapted to stretch the tissue paper after clamping between the tensioning and clamping frames.

3. A printing frame comprising in combination a lower frame, an upper frame, a clamping frame therebetween, said frame being open in the center, said clamping frame being adapted to engage a sheet of tissue paper between the lower peripheral surfaces thereof and the upper peripheral surfaces of the lower frame, and means in the upper frame to hold a negative at proper position from the sheet of tissue paper smoothed between the clamping frame and the upper and lower frames, whereby light may be transmitted through the paper and negative.

4. A printing frame as claimed in claim 3, having in addition a relatively co-acting peripheral bead and groove adjacent the said peripheral surfaces, adapted to engage the tissue paper between the upper and lower frames and on the inside of the clamping frame to thereby stretch the paper.

5. A printing frame as claimed in claim 3, having in addition a tensioning frame attached to the lower frame surrounding its inner opening over which the tissue paper is adapted to spread when clamped by the clamping frame, said tensioning frame engaging the paper and tightening same adjacent the periphery of the clamping frame.

6. A printing frame comprising in combination a lower frame, an upper frame, a thin clamping frame, said frames having aligned openings therethrough, hinges securing said frames together, the lower frame having grooves extending around the openings and inside of the opening in the clamping frame, beads secured to the upper frame adapted to fit the said grooves, whereby a sheet of tissue paper may be clamped be-

tween the clamping frame and the lower frame and stretched by pressing the beads into the grooves in the lower frame.

7. A printing frame as claimed in claim 6, having in addition means on the upper frame to retain a negative in adjusted position relative to a sheet of tissue paper stretched in the frame.

8. A printing frame as claimed in claim 6, having in addition a tensioning frame having a smooth surface attached to the lower frame and on the inside of the grooves and beads over which the tissue paper is adapted to be stretched.

15 9. A printing frame as claimed in claim 6,

having in addition a tensioning frame formed of smooth metal secured to the lower frame inside of the grooves and beads and having also a recess in the upper frame adapted to hold a negative.

20

10. A printing frame as claimed in claim 6, in which the hinges have straps secured to the upper and lower frames, a hinge pin retaining said straps in hinged relation and an eye secured to the clamping frame and occupying a central position on the pin between the upper and lower frames.

In testimony whereof I have signed my name to this specification.

WILLIAM DE PAUK.
